UNITED STATES PATENT OFFICE.

ALBERT SPILLMAN, OF NORTH TONAWANDA, NEW YORK.

DESIGN FOR A HEATER FOR AUTOMOBILES.

Application filed September 9, 1927. Serial No. 23,335. Term of patent 3½ years.

To all whom it may concern:

Be it known that I, ALBERT SPILLMAN, a citizen of the United States of America, and a resident of the city of North Tonawanda, county of Niagara, in the State of New York, United States of America, have invented a new, original, and ornamental Design for a Heater for Automobiles, of which the following is a specification, reference being made to the accompanying drawing, forming a part thereof.

I claim:

The ornamental design for a heater for automobiles as shown.

ALBERT SPILLMAN.
